APPARATUS FOR DEPITHING BAGASSE
Leo Freeman, Baton Rouge, La., assignor to Grundler
Crusher & Pulverizer Co., St. Louis, Mo., a corporation
of Missouri

Filed Oct. 27, 1961, Ser. No. 148,169
16 Claims. (Cl. 19—34)

This invention relates in general to certain new and useful improvements in methods for depithing bagasse and to improved apparatus therefor.

It is the primary object of the present invention to provide a novel method of processing bagasse whereby a very efficient and complete separation between pith and fiber is achieved.

It is also an object of the present invention to provide a bagasse depithing process of the type stated that can be conducted in multiple stages whereby bagasse can be removed at any of the stages.

It is another object of the present invention to provide apparatus that is capable of removing the pith from bagasse without impairing the value of the fiber.

It is also an object of the present invention to provide methods for separating a pith-containing fibrous material such as bagasse into pith and fiber in a simple, efficient and continuous manner without macerating the fibers or materially shortening them.

It is a further object of the present invention to provide a bagasse depithing apparatus of the type stated which is highly economical and efficient.

With the above and other objects in view, my invention resides in the novel features of form, construction, arrangement, and combination of parts presently described and pointed out in the claims.

In the accompanying drawings—

FIG. 1 is a front elevational view of bagasse defiberizing apparatus constructed in accordance with and embodying the present invention;

FIG. 2 is a side elevational view of the bagasse depithing apparatus shown in FIG. 1;

FIG. 3 is a fragmentary sectional view taken along line 3—3 of FIG. 2;

FIGS. 4 and 5 are fragmentary sectional views taken along lines 4—4 and 5—5, respectively, of FIG. 3;

FIG. 6 is a fragmentary sectional view taken along line 6—6 of FIG. 2;

FIGS. 7 and 8 are fragmentary sectional view taken along lines 7—7 and 8—8, respectively, of FIG. 6;

FIG. 9 is a fragmentary perspective view of the beater arm forming a part of the present invention;

FIG. 10 is a fragmentary sectional view taken along line 10—10 of FIG. 7;

FIG. 11 is a fragmentary sectional view taken along line 11—11 of FIG. 2; and

FIG. 12 is a fragmentary longitudinal sectional view of a modified form of second stage pith separator constructed in accordance with and embodying the present invention.

Referring now in more detail and by reference characters to the drawings, which illustrate practical embodiments of the present invention, the apparatus consists of a fed conveyor A, a bale-breaker B, a first stage or primary separator C, a second stage or secondary separator D, a third stage or tertiary separator E, a discharge conveyor F, a primary cyclone collector G, and a secondary cyclone collector H, all connected in series substantially as shown in FIGS. 1 and 2 and presently to be described in more detail.

The feed conveyor A is preferably of the conventional roller-supported continuous-belt type and, therefore, need not be described or illustrated in particular detail. It is sufficient for present purposes to point out that the feed

2

conveyor A must be of sufficient size, strength, and speed to convey bagasse bales x to the bale-breaker B. Although, in the drawings, the bale x is shown as being tied, it is usual practice for a workman to be stationed along the feed conveyor A and remove the bale ties just before the bale is discharged over the end of the feed conveyor A. It is also quite likely that the depithing apparatus of the present invention would be installed in, or adjacent to, a sugar plant so that the bagasse would be deposited upon the feed conveyor in unbaled or loosely consolidated form. It should, therefore, be understood that the present invention is in no way limited to the form or condition in which the bagasse is deposited upon the feed conveyor A.

15 The first stage or primary pith separator C comprises a semi-cylindrical top member 1 provided along its longitudinal margins with horizontal flanges 2, 3, secured by means of bolts 4, 5, to matching flanges 6, 7, formed along the longitudinal margins of a semi-cylindrical screen

8 preferably having the same radius as the top member 1. Suitably mounted across the ends of the top member 1 and screen 8 are end walls 9, 10, thereby forming a horizontal cylindrical beater-chamber 11. Bolted to and extending through one end of the top member 1 is a tubular intake chute 12 by which the bagasse is transferred from the bale-breaker B to the interior of the pith separator C. Similarly mounted in the other end of the pith separator C is a tubular discharge pipe 13 by which fiber is delivered to the intake end of the secondary separator D.

20 Rigidly bolted to the underside of the screen 8 is a discharge pan 14 provided with two vertical side walls 15, 16, integrally provided on their lower margins with two inwardly and downwardly converging bottom walls 17, 18, which, in turn, merge into a downwardly projecting discharge pipe 19, the latter being connected by an air-pipe 20 to a centrifugal blower 21, the discharge side of which is likewise connected by an air-pipe to the intake of a cyclone separator 22. In order to provide free entry of air into the interior of the beater-chamber 11, the top member 1 is provided with a plurality of apertures 23, as best seen in FIG. 3.

25 The end walls 9, 10, are respectively provided with concentric apertures 24, 25, for accommodating an axially extending agitator shaft 26 mounted in bearings 27, 28, operatively supported in bearing housings 29, 30, bolted or otherwise rigidly secured to horizontally extending brackets 31, 32, which are, in turn, rigidly secured upon the outer faces of the end walls 9, 10, respectively. The rotatable agitator shaft 26 is driven by a conventional electric motor 33 which is also mounted on the bracket 31. Mounted on the shaft 26 by means of set screws 34 is a series of agitator elements 35, each having a central hub 36 and diametrically opposite paddle-like blades 37 which are provided with a pitch that will propel the bagasse axially through the beater-chamber 11 and subject it to a substantial degree of disintegration before reaching the discharge pipe 13. Also mounted on the shaft 26 and secured thereto by a set screw 38 is a fiber discharging element 39 having a hub 40 and relatively large non-inflected blades 41, 42 to propel the fiber into the discharge pipe 13.

30 The blower 21, the cyclone separator 22, and the motor 33, are conventional and, therefore, are not illustrated nor described in detail herein.

35 The blower 21, the cyclone separator 22, and the motor 33, are conventional and, therefore, are not illustrated nor described in detail herein.

40 The discharge pipe 13 is preferably rectangular in cross-sectional shape and opens laterally into the upper end of the second stage pith separator D. Communicating with the rectangular discharge pipe 13 at the point of entry into the separator D is a second rectangular discharge pipe 43 for optionally delivering fiber from the first stage separator C to a conveyor 44. A valve plate 45 is pivotally mounted in the passageway of the discharge

70

pipe 13 at the region of connection to the discharge pipe 43 by means of a shaft 46 which is provided with an externally accessible handle 47 for providing optional delivery between either of the two discharge pipes 13, 43.

The second stage pith separator or so-called "scrubber" D comprises a semi-cylindrical top member 48 provided along its longitudinal margin with outwardly extending flanges 49, 50, which are tightly secured by means of a series of bolts 51 to matching flanges 52, 53, formed integrally along the upper longitudinal edges of a bottom member 54 having spaced parallel side walls 55, 56, and downwardly converging angular bottom walls 57, 58. Along their transverse margins, the top member 48 and the bottom member 54 are respectively provided with end flanges 59, 60, 61, 62. Bolted to and extending transversely across the end flanges 59, 61, is a flat lower end wall 63 and similarly bolted to and extending transversely across the end flanges 60, 62, is an upper end wall 64, thereby forming an enclosed chamber 65. As may be seen by reference to FIG. 6, the second stage pith separator D is mounted in some conventional manner by suitable structural members (not shown) so as to be disposed with its longitudinal axis at a moderate downwardly inclined angle from its upper end wall 64 to its lower end wall 63. The chamber 65 is provided, upon its interior surface, with two axially spaced sets of trunnion supported rollers 66a, 66b, 66c, 67a, 67b, 67c, respectively supporting mounting rings 68, 69, which, in turn, are secured externally to and operatively support a rotating screen 70 which consists of an elongated screen element 71 which is preferably hexagonal in cross-section and tapers slightly from its upper end to its lower end, such lower end being rigidly mounted in a cylindrical screen element 72 which is substantially larger in diametral size than the uppermost portion of the hexagonal screen element 71. At its upper end, the hexagonal screen element 71 is provided with an inwardly turned annular flange 73 which defines a relatively large opening 74 for receiving the stream of fiber which is discharged thereinto from the oblique spout portion 75 which extends through the end upper wall 64 from the lower end of the discharge pipe 13. Similarly, the lower end of the cylindrical screen element 72 is provided with an inwardly turned annular flange 76 which defines a relatively large opening 77 communicating to the open upper end of a discharge spout 78 which is connected to the upper end of, and forms a part of, a downwardly extending discharge pipe 79.

Rigidly mounted upon, and encircling, the hexagonal screen element 71 approximately midway between the upper end wall 64 and the lower end wall 63 is a ring-type worm gear 80 which meshes with a driving worm 81 pinned upon a shaft 82 which is, in turn, journaled in bearings 83, 84, the latter being mounted in, and extending through, the top member 48. At one end, the shaft 82 projects outwardly and is operatively connected to a conventional electric motor 85 mounted upon a horizontal bracket 86 which is welded or otherwise rigidly secured upon the external face of the top member 48, all as best seen in FIG. 8.

The end walls 63, 64, are provided with concentric apertures 87, 88, for accommodating an elongated beater-shaft 89 which extends axially through the second stage pith separator D and is operatively journaled in bearings 90, 91, which are, in turn, mounted in bearing-supports 92, 93, the latter being respectively supported on brackets 94, 95, which are welded or otherwise rigidly secured to the outer faces of the end walls 63, 64. The lower end of the shaft 89 is operatively connected to an electric motor 96 which is also rigidly secured upon the bracket 94. At uniformly spaced intervals along its length between the end walls 63, 64, the shaft 89 is provided with a series of beater-arms 97, each being integrally provided at its inner end with a hub 98 which is secured to the shaft 89 by means of a set screw 99. The beater-arms 97 are relatively flat and blade-like in shape, being angu-

larly deflected so as to propel the fibers from the upper end to the lower end of the rotating screen 70. Each of the beater-arms 97 is, furthermore, provided at its outer end with a short piece of free-swinging chain 100 which is of such length as to almost, but not quite, touch the surfaces of the screen elements 71, 72, as best seen in FIGS. 7 and 8. Moreover, the direction of rotation of the electric motors 85, 96, is such that the screen 70 will rotate in one direction and the shaft 89 will rotate in the opposite direction. In other words, the shaft 89 and beater-arms 97 are counter-rotating with respect to the screen 70.

The downwardly converging walls 57, 58, of the bottom member 54 actually funnel into a downwardly projecting discharge spout 101 which is connected to the upper end of a discharge pipe 102, which is, in turn, connected to the intake side of a conventional centrifugal blower 103. The discharge side of the centrifugal blower 103 is connected by an air-pipe 104 to a second conventional cyclone separator 105.

As will be seen by reference to FIGS. 7 and 8, the end walls 63, 64, are provided with a plurality of air inlet apertures 106, each of which is covered over with a piece of screen wire or similar foraminous material 107 held in place by an annular frame 108, the latter being rigidly secured by screws 109. The screen covered apertures 106 are relatively large so that air may be freely drawn therethrough and through the chamber 65 by means of the blower 103. It will also be noted, by reference to FIG. 6, that the beater-arms 97 which are located within the hexagonal screen element 71 are oriented at 90° to each other around the shaft 89 and the two beater-arms 97 which are located in the cylindrical screen element 72 are in diametral orientation with respect to each other. The discharge pipe 79, at its lower end, opens into an inverted Y so as to provide a lateral discharge spout 110 extending angularly in one direction and a lateral tubular chute 111 extending angularly in the opposite direction. The discharge spout 110 opens downwardly into a short vertical discharge leg 112 which discharges downwardly onto a fiber conveyor 113. The tubular chute 111, in turn, opens downwardly into the third stage or tertiary separator E, which is of substantially the same type as that described in United States Patent No. 2,825,935, issued Mar. 11, 1958. Inasmuch as the tertiary separator E is fully described in said patent, it is sufficient, for present purposes, to note that the tertiary separator E includes a pith discharge chute 114 which discharges downwardly onto a conveyor 115 and a fiber discharge chute 116 which discharges downwardly onto a conveyor 117. In the region of the separator between the discharge spout 110 and the discharge chute 111 is a horizontal shaft 118 which operatively supports a deflector plate 119 and is externally provided with a handle 120. By shifting the deflector plate from the position shown in full lines to the position shown in dotted lines in FIG. 11, it is possible to direct the flow of fiber to the conveyor 113 or to the tertiary separator E.

It will also be noted by reference to FIGS. 1 and 2 that the cyclone separators 22 and 105, respectively, have air-discharge ducts 121, 122, and pith discharge spouts 123, 124.

The bagasse enters the first stage or primary separator C through the tubular intake chute 12 and is subjected to the beating action of the paddle-like blades 37 which break up the bagasse and loosen a large percentage of the fibers and pith. The pith is drawn downwardly through the screen 8 and delivered into the cyclone separator 22. The fiber, which still contains a certain percentage of pith, drops over the end of the screen 8 into the discharge pipe 13 and is delivered into the rotating hexagonal screen element 71 of the secondary separator or so-called "scrubber" D, in which it is again subjected to beating action as it progresses down the inclined hexagonal screen element 71 and into the screen element 72. The air which is being drawn through the secondary separator D by means of the blower 103 will draw the pith through the

openings of the screens and the relatively clean pith-free fibers will drop down through the discharge pipe 79. If, for any reason, it should be desirable or necessary to remove the partially cleaned fibers without subjecting them to further cleaning or scrubbing action in the secondary separator or scrubber D, this can be accomplished by moving the valve plate 45 from the position shown in full lines to the position shown in dotted lines in FIG. 6. After the fiber has been further cleaned in the secondary separator or scrubber D, it may optionally be discharged upon the conveyor 113 or may be subjected to a further and final polishing operation in the tertiary separator E. The pith from the secondary separator or scrubber D is conveyed by means of the blower 103 to the cyclone separator 105. If the fiber is given a final polishing operation in the tertiary separator E, the very small amount of pith developed will be deposited on the conveyor 115 and the substantially pure pith-fiber will be deposited on the conveyor 117 for transportation to some suitable point of ultimate use.

It is possible to provide a modified form of the second stage pith separator D', as shown in FIG. 12, which is similar in most respects to the previously described second stage pith separator D, except that means are provided for washing the pith and fiber during the separating action. The secondary unit D', similarly consists of an open-ended hexagonal revolving screen 125 that is supported at its right transverse margins by spool-shaped rollers 126, which are similar in all respects to the previously described rollers 66a, 66b, 66c, and 67a, 67b, 67c. A hollow agitator shaft 89' is rotatably mounted in bearings 127 which are, in turn, mounted in a bearing housing 128, the shaft 89' being provided with a central axial bore 129. Welded to the shaft 89' are axially spaced radially extending agitator blades 130 having axially extending central bores 131 which communicate with the central bore 129 of the agitator shaft 89'. Each agitator blade 130 is also provided with a U-shaped bight portion 132 at its outer end having transversely aligned apertures 133 for accommodating a bolt 134 for rigidly attaching a length of chain 135 to the blades 130. The blades 130 are, moreover, provided with a series of radially extending tubular channels 136 which communicate with the axially extending central bores 131. One end of the hollow agitator shaft 89' is mounted in a stuffing box 137, which is, in turn, mounted on a horizontal bracket 138 and is provided with a central bore 139 sized to accommodate the shaft 89'. Moreover, the stuffing box 137 is provided with an annular sealing ring 140 for maintaining a fluid-tight seal around the outer peripheral surface of the shaft 89' and is finally provided with an axially extending tubular channel 141 in communication with the bore 139. A fluid coupling 142 is threadedly attached to the outer end of the channel 141 for connection to any suitable source of rinse water.

The second stage pith separator D' operates in a manner similar to the manner previously described pith separating unit D. The hexagonal screen 125 rotates in one direction as the agitator shaft 89' rotates in an opposite direction. Water is admitted to the rotating hollow shaft 89' through the stuffing box 137. As the tubular channels 136 communicate with the axial central bore 131 of the agitator blade 130 which, in turn, communicates with the bore 129, water under pressure will be forced out of the tubular channels 136 providing a scrubbing and washing action for separating the pith and fiber. Moreover, this washing and rinsing action will tend to cleanse the chain links 135 and screen 125.

It should be understood that changes and modifications in the form, construction, arrangement, and combination of the several parts of the depithing processes may be made and substituted for those herein shown and described without departing from the nature and principle of my invention.

Having thus described my invention, what I claim and desire to secure by Letters Patent is:

1. An apparatus for removing pith from fibrous plant stalks such as bagasse and the like; said apparatus comprising a first separator unit for separating the plant stalks into pith and fiber, the first separator unit having an inlet for receiving the plant stalks, an outlet for expelling the separated fibers, and a pith collecting member for receiving the separated pith; a second separator unit including a housing, a screen rotatably mounted within the housing, the housing having an inlet which opens into one end of the screen, an outlet which communicates with the opposite end of the screen, and a pith collecting member disposed beneath the screen, a beater shaft rotatably mounted on the housing and extending coaxially through the screen, a plurality of blades mounted on the beater shaft and being pitched for propelling the fibers along the interior of the screen from the inlet to the outlet, and power means for rotating the beater shaft and the screen; and a first discharge chute interconnecting the outlet of the first separator unit with the inlet of the housing forming part of the second separator unit, whereby the fiber discharged from the first separator unit is conveyed to the second separator unit for further depithing.
2. An apparatus according to claim 1 in which the beater shaft and screen rotate in opposite directions.
3. An apparatus according to claim 2 and further characterized by pith collecting means, a first discharge pipe interconnecting the pith collecting means and the pith collecting member of the first separator unit; and a second discharge pipe interconnecting the pith collecting means and the pith collecting member of the second separator unit.
4. An apparatus according to claim 3 in which the pith collecting means includes first and second cyclone collectors connected to the first and second discharge pipes, respectively, said apparatus being further characterized by first and second blowers interposed in the first and second discharge pipes so as to establish an air stream therein for conveying the pith to the cyclone collectors.
5. An apparatus according to claim 2 in which the screen includes a first screen element and a second screen element, which is greater in transverse width than the first screen element, the second screen element being located adjacent the outlet in the housing.
6. An apparatus according to claim 5 in which the first screen element tapers slightly toward the second screen element.
7. An apparatus according to claim 5 in which the first and second screen elements are of polygonal and cylindrical cross-sectional shape, respectively.
8. An apparatus according to claim 7 in which the common axis of the screen and beater shaft is tilted slightly downwardly toward the outlet of the housing.
9. An apparatus according to claim 7 and further characterized by chain-like elements mounted on the ends of the blades for circumferential movement in close proximity to the inner surfaces of the screen elements.
10. An apparatus according to claim 1 in which the common axis of the screen and beater shaft is tilted downwardly toward the outlet of the second separator unit.
11. An apparatus according to claim 1 in which the screen has a polygonal cross-sectional shape.
12. An apparatus according to claim 1 in which the screen has a hexagonal cross-sectional shape.
13. An apparatus according to claim 1 and further characterized by chain-link elements mounted at the ends of the blades for circumferential movement in close proximity to the inner surface of the screen.
14. An apparatus according to claim 1 in which the screen tapers slightly from the inlet to the outlet of the second separator unit.
15. An apparatus according to claim 1 and further characterized by a valve interposed in the first discharge chute for optionally directing the fiber to the second sep-

arator unit or out of the first discharge chute prior to the second separator unit.

16. An apparatus according to claim 15 and further characterized by a third separator unit for further depthing the fibers discharged from the outlet of the second separator unit, a second discharge chute interconnecting the outlet of the second unit and the third unit, and a valve interposed in the second discharge chute for optionally directing the fiber to the third separating unit or withdrawing it from the apparatus.
